MATRIX RETAINER

David Reiter, Woodside, Long Island, N. Y.

Application July 11, 1946, Serial No. 682,897

5 Claims. (Cl. 32—63)

1

This invention pertains to a matrix retainer particularly adapted for use in the profession of the art of dentistry.

An object of the present invention is the provision of an improved retainer for holding a dental matrix band in such a manner that the band will conform to any shape of tooth.

Another object of the present invention is the provision of a simple, positive, and inexpensive dental matrix band retainer with the band being so flexibly held about a tooth as to allow the band to conform to any shaped tooth so that as a cavity in the tooth is filled the material employed to fill the cavity can be condensed without the filling material escaping out of the cavity.

The above and numerous other objects will become apparent from the succeeding description considered together with the accompanying drawing, wherein:

Figure 1 is a plan view of a matrix band retainer embodying the present invention.

Figure 2 is a side elevational view of the matrix band retainer illustrated in Figure 1.

Figure 3 is a longitudinal sectional view taken along the lines 3—3 of Figure 2, looking in the direction of the arrows.

Figure 4 is a view depicting a part of the matrix band retainer applied to a tooth.

Referring now in detail to the various figures of the drawing, wherein like reference characters indicate like parts, the numeral 1 is employed to designate, in a somewhat general manner, a dental matrix band retainer exemplifying a form of the present invention.

In the practice of dentistry it has been found that unless a matrix band is arranged to conform completely to a tooth about a location to be filled that the filling material, be it of wax or precious or semi-precious material, will upon being compressed within the cavity, be urged between the matrix band and tooth outwardly of the cavity. This undesirable condition wherein a matrix band has a portion thereof spaced from an outer surface of a tooth not only prevents a solid packing of the cavity but it also presents an outlet for the waste of material and does not afford a smooth, even, uninterrupted surface where the outer surface of the tooth meets the outer surface of the filling. In order to eliminate the above noted undesirable condition there is provided in the present structure a holder or retainer 2 comprising a frame or housing 3 being formed preferably by a top and bottom leg 4 extending longitudinally of the frame in parallel spaced relation to one another. The top and bot-

2

tom legs are joined together at or adjacent their forward extremities by a front or forward wall 5 and at or adjacent their rear extremities by a rear or back wall 6. The front wall is desirably of the same or similar cross-sectional area as the top and bottom legs while the rear wall may, if desired, be formed of an increased thickness but being rather circular in configuration so as to extend beyond the extended limits of the legs. By so forming the rear wall an appreciable bearing area will be presented for the accommodation of related components hereinafter described. The connecting legs and walls of the frame define an enclosed guideway or opening 7 therebetween.

Positioned within the frame opening or guideway is a block or movable member 8 having a body portion 9 arranged with oppositely facing and disposed channels 10 accommodating or receiving adjacent portions of the top and bottom legs so as to form an interlock between the block and frame. As will be noted therefore the block is arranged to move in a definite and fixed path in the frame guideway. Extending longitudinally of the frame is a barrel, yoke or tubular sleeve 11 positioned within the guideway and formed integrally with the block as a rigid part thereof. The sleeve is interiorly threaded and extends in a direction toward the rear wall.

Movably mounted in the rear wall and carried thereby is a power means 12 having a head or knob portion 13 forming a means by which the power means may be manipulated. The head is positioned outward of the frame from the rear wall and interposed between the knob and rear wall is a washer 14 which, if desired, may be eliminated from the structure but it is shown and described herein because in addition to forming a wear plate it also functions as a spacer permitting the portion of the knob grasped between the thumb and forefinger of an operator to be spaced an appreciable or convenient distance from the back wall. Outstanding from one or an inner end of the knob is a stem 15 extending through suitable aligned apertures in the washer and rear wall to be centrally positioned within the guideway and threadedly associated with the block barrel. Any manipulation of the power means to effect a rotary motion thereof will result in the block moving along or within the guideway in a direction toward or away from the front wall depending entirely upon the direction of movement of the power means. In order to prevent the power means from moving axially or longitudinally thereof the stem is provided with a thrust

collar 16 locked to the stem by any desirable means such as the illustrated set screw 17 and the collar is desirably in abutting relation with the rear wall within the guideway. Each leg at its juncture with the rear wall is formed with a relief 18 to afford ample clearance for the collar and its associated set screw. Thus while the knob prevents a movement of the power means inwardly of the frame the collar prevents movement of the power means outwardly of the frame and the power means is free to rotate about its longitudinal axis to move the block in a selected direction.

The block is provided with a transversely and centrally disposed bore through which there extends a shaft, axle or pinte 19. The pinte may be arranged to remain stationary with or move in a pivotal manner relative to the block just so long as it is arranged to move along the guideway in response to a corresponding movement of the block. The shaft has its respective ends extending beyond the transverse limits of the block for a predetermined distance and for a purpose to be made hereinafter apparent. Disposed at each side of the block is a post or standard or swivel member 20 having a countersunk, centrally disposed opening occupied by a correspondingly formed journal 21 of the shaft end. Each post is arranged locked to a pinte extremity and arranged to move relative thereto and relative to one another about the axis of the shaft. Extending entirely through each post in a direction longitudinally of the retainer is a slot or passageway 22 and through each passageway there extends an extremity of a continuous, uninterrupted dental matrix band 23 formed of extremely light gauge stainless steel or any desired material. Each post, in axial alignment with the pinte, is provided with an interiorly threaded hole which is occupied by a holding means or headed set screw 24. The headed set screws may be manipulated in a rotary manner to move inwardly or outwardly of the post hole. By a proper manipulation of the headed set screws, ends thereof which are free to project into the post slots, lock a dental matrix band to the posts so that any movement of the block will be reflected in the dental matrix band. The post holes are preferably, as stated, in alignment with the pinte so that upon assembly of the components, tools may be inserted in the post holes to form the countersunk heads on the pinte.

When a dental matrix band is to be associated with a tooth that has been previously prepared by drilling the required or necessary cavity, the band is inserted into the post slots and the headed set screws manipulated in such a manner as to bind the respective ends in associated posts to form a loop 25 of sufficient dimensions to extend around the tooth to be treated. The matrix band thus screwed to the retainer is then placed loosely about the tooth to be treated at which time the power means is manipulated to draw the block toward the frame front wall. As the band is drawn against the tooth the frame end wall is urged toward and against the tooth and as the band tightening process continues the posts will rotate individually about their common pinte axis to thereby lend themselves or adjust themselves to accommodate stresses built up in the matrix band. It has been repeatedly proven in actual practice that in a structure such as herein illustrated and described, a matrix band will conform to the particular configuration of any shaped tooth to present a barrier absolutely closed

5 at the bottom at or adjacent the root of the tooth so that the filling material will not escape and assist the remaining portion of the tooth in forming a completely surrounded cavity that may be packed with filling material. It has also been found that no dressing need be administered by the dentist to present a smooth, even, uninterrupted outer surface at the filling-tooth juncture line after the assemblage has been removed from the patient. This highly desired and accomplished result resides in the distinct individual pivotal mountings of the posts because they are arranged to adjust themselves independently of one another to permit the matrix band to conform to a configuration controlled by the particular shape of the tooth being treated.

10 The front wall of the frame and preferably the adjacent portions of the legs are bifurcated as at 26 and thus two transversely spaced feet 20 27 are formed in the related end of the frame to form non-slipping or non-skidding abutments arranged to bear against a tooth.

15 From the above it will be noted that various changes and alterations may be made to the illustrated and described construction without departing from the spirit of the invention and scope of the appended claims.

I claim:

20 1. In a dental matrix retainer, the combination of, a frame member having a central guideway, power means pivotally mounted on said frame member and having a portion extending into said guideway, a block arranged in said guideway and movable longitudinally thereof by said power means, a post pivoted to said block at each side thereof, a slot in each post, a matrix band having ends thereof extending through said post slots and means carried by said posts for fixing said matrix band to said posts.

25 2. In a dental matrix retainer, the combination of, a frame having a longitudinal opening, means rotatably mounted on said frame and having a portion thereof extending into said opening, a block slidably carried by said frame within said opening and arranged for movement by said means, a post pivotally mounted to each side of said block, a slot extending through each post, a matrix band having its respective ends extending through said post slots, and rotatable means carried by said posts for holding said matrix band.

30 3. In a dental matrix retainer, the combination of, a frame having a longitudinal opening, means rotatably mounted on said frame and having a portion thereof extending into said opening; a block slidably carried by said frame within said opening and arranged for movement by said means, a post pivotally mounted to each side of said block, a slot extending through each post, a matrix band having its respective ends extending through said post slots, and rotatable means carried by said posts and extending into said slots for holding said matrix band fixed to said posts.

35 4. In a dental matrix retainer, the combination of, a frame having a longitudinal opening, power means rotatably mounted on said frame and having a portion thereof extending into said opening, a block slidably carried by said frame within said opening and arranged for movement longitudinally of said frame by said means, pivot means carried by said block, a post at each side of said block and carried by said pivot means, a slot extending through each post, a flexible matrix band having its respective ends extending 40 through said post slots, and clamping means car-

ried by said posts and extending into said slots for locking said matrix band and posts together.

5. In a dental matrix retainer, the combination of, a frame having a longitudinal opening, means rotatably mounted on said frame and having a portion thereof extending into said opening, a block having oppositely facing grooves occupied by associated parts of said frame, said block being arranged to slide longitudinally of said frame by force supplied by said power means, pivot means carried by said block, a post at each side of said block and carried by said pivot means, said posts being arranged to rotate about said pivot means relative to one another, a matrix band having respective ends thereof associated with said posts, 15

and rotatable means in axial alignment with said pivotal means for locking said matrix band ends to said posts.
